UNITED STATES PATENT OFFICE

GEORGE A. LANSBERRY, OF KANSAS CITY, MISSOURI, AND LOUIS A. HARTMAN AND VICTOR A. JASPERSON, OF TOPEKA, KANSAS, ASSIGNORS TO THE AMERICAN BENCH COT COMPANY, OF TOPEKA, KANSAS, A CORPORATION OF KANSAS

BENCH COT

Application filed November 21, 1929. Serial No. 408,785.

This invention relates to folding furniture and particularly to a novel device which may be termed a bench cot, and the primary object of the invention is the provision of a novelly constructed article having desirable features when the device is used either as a folding cot, bench, or table.

One of the objects of the present invention is to provide a bench cot or similar article of furniture which embodies new and novel means for supporting the flexible top when the same is in the operative position, which means incorporates an adjusting device operable by the user as heavy usage requires taking up slack caused by said usage or lending more positive support to the flexible top forming a part of a folding cot.

Still another object of the instant invention is the provision of novel reinforcing strips co-extensive with the canvas top of the folding cot, two of said reinforcing strips being stitched to the canvas along the lower side thereof at the outer edges in such a manner as to receive and distribute a great portion of the weight when the cot is in use.

An even further object of this invention is the contemplation of novel engaging members which, when used in the construction of this device performs a number of functions one of which is the slidably supporting of a novel continuous webbing strip which co-act with the above mentioned reinforcing strips to equalize the weight placed upon the cot top.

A yet further object of the present invention is the provision of a combined bench and folding cot having a series of hingedly inter-connected leaves adapted to lock the device against movement when the series of leaves are disposed in the operative position.

Another, and one of the main objects of this invention is to provide a combined bench and folding cot which is strong and durable, inexpensive to manufacture and extremely efficient in its operation, means being provided through-out its construction for the lending of strength and durability yet not appreciably adding to its bulk and weight.

Many minor objects will appear during the course of the detailed specification refer-

ring to the accompanying drawings wherein but one embodiment of the invention has been illustrated.

In the drawings:

Figure 1 is a side elevation of a combined bench and folding cot made in accordance with this invention showing the same in the open position and usable as a cot. 55

Fig. 2 is an inverted plan view of the same. 60

Fig. 3 is an edge view of the combined bench and folding cot showing the same in the closed position. 65

Fig. 4 is another edge view of the device showing the same partially extended and locked in position to be used as a table. 70

Fig. 5 is an enlarged fragmentary detailed view taken through the articulated upper ends of the lazy tong bars, and 75

Fig. 6 is an end view of the completely closed device as shown in Fig. 3. 80

With particular reference at this time to the specific construction of the novel combined bench and folding cot illustrated in the accompanying drawing wherein like reference characters refer to similar parts throughout the several views, the numeral 8 indicates the well known lazy tong side frames of a folding cot which are made up of lazy tong bars 10 articulated as at 12 intermediate the ends of said bars 10 and as at 14 at the lower ends of the bars 10. The upper articulated ends of lazy tong bars 10 are pivotally secured together by a specially constructed eye bolt 16 having its eye disposed inwardly. The eyes of the set of eye bolts 16 along one lazy tong side frame 8 being disposed inwardly and toward the eyes of the eye bolt 16 of the opposite lazy tong side frame 8. 85

In assembling the device the outwardly projecting screw threaded portion 18 of eye bolts 16 first receives a nut 20 which bears against lazy tong bar 10 to hold the upper ends of these bars in pivotal relation. Flexible top 22 may then be passed over the outer end of eye bolts 16 after which the cap nut 24 is screwed in place. This cap nut precludes flexible top 22 from jumping free of eye bolt 16 and also houses and lends a 90

pleasing appearance to the threaded end of eye bolt 16 which normally would be presented to view. Flexible top 22 may be made up of the well known canvas material and in carrying out this invention the same should be longitudinally reinforced through the use of longitudinally extending reinforcing strips 26 which are attached at their ends to the end tie members 28 of the lazy tong sides.

These reinforcing strips 26 should be several in number and the same should be suitably spaced apart through-out the width of the flexible top 22. As shown in Fig. 5 a reinforcing strip 26 should be stitched to the lower side of flexible top 22 adjacent the two edges. In stitching this strip 26 the outer line of stitching should be in the form of grommets 28 which secure the outer edges of strip 26 and flexible top 22 together. If desired, a line of stitching such as shown at 30 may also be provided. After the grommets have been set or the stitching along the outer edge has been done, the inner line of stitching 30 should be placed only after a fullness has been caused to take place in the flexible top between these two lines of stitching. As shown in Fig. 5 this construction causes reinforcing strips 26 to bear against the ends 30 of lazy tong bars 10 and to be stretched tightly around the top of the lazy tong side to engage eye bolts 16. In this fashion weight upon the flexible top 22 which would normally cause the top to wear at this point 35 is transmitted directly to this reinforcing strip 26.

As is customary in constructing folding devices wherein the lazy tong principle is used, braces 32 are provided which extend 40 across from one set of lazy tong side frames to the other. It may also be desirable to interpose angle blocks 34 between these braces 32 and the lazy tong bars 10.

To even further reinforce flexible top 22 45 and to carry out one of the basic principles of this invention, the device is provided with a continuous webbing strip 36 which is threaded through eye bolts 16 to slidably engage the same and to join the two sets 50 of lazy tong side frames in crosslaced fashion as shown in Fig. 2.

In threading this continuous webbing strip 36 through the eye bolts and across 55 from side to side, a system of threading similar to that shown in Fig. 2 should be followed, not necessarily however, but in order that the ends of the continuous webbing strip 36 might be in a position to be joined by a tension adjusting device 38 which in 60 the instance shown is the well known turn-buckle having right and left threads which permits drawing together or allowing the ends of continuous strip to be pulled apart as the same is operated. Continuous webbing strip 36 is positioned beneath the longi-

tudinally extending reinforcing strips 26 and when weight is placed upon flexible top 22 a bringing together of these elements just named distributes the weight through-out the entire structure in a manner which does not permit a strain to be imparted to any particular point through-out the construction. This point is highly advantageous in folding devices of this character and even after the device has been used slack can be 70 taken out of the continuous webbing strip 36 and the same moved to the properly adjusted position through the novel and extremely simple construction just described. 75

This combined bench and folding cot is 80 useable as a bench such as shown in Figs. 3 and 6 or as a table such as shown in Fig. 4 and it is to carry out this object of the invention that a series of leaves 40 are provided all of which leaves 40 are hingedly 85 inter-connected as at 42 so that any predetermined number of the leaves 40 might be used. When the device is completely folded as shown in Fig. 3 this series of leaves 40 acts as a housing for the upper end and 90 completely obscures the flexible top 22.

It is obvious that any number of leaves 40 might be hingedly inter-connected to form a suitable table top to over-lie the lazy 95 tongs when they are extended as shown in Fig. 4. When the device is used as a cot these leaves 40 would be positioned at the head as shown in Fig. 1. A locking device is provided which may be made up of a hook 44 carried by the lazy tong side frames at appropriate points where the same may be moved into engagement with rings 46 carried by the outer-most edge of the last leaf 40 of the series. As shown in Figs. 1, 3 and 4 one of the leaves 40 of the series 100 should be hingedly connected as at 48 to the ends of the side frames 8. Through this construction and the proper positioning of the locking members, a table or the like 105 such as shown in Fig. 4 will be rigidly held together and the lazy tong sides 8 kept from extending or contracting while the device is in use.

While one specific form of the invention 110 has been shown it is understood that many modifications might be made and various refinements added such as the locking bar 50, used to preclude closing of the lazy tong sides when the same is in use as a cot, and 115 many other devices not herein shown or mentioned.

The many uses and operation of the device have been made clear throughout the 120 specification.

While one form of the invention has been 125 shown and described in detail, it is understood that many modifications might be made in constructing devices embodying the 130 invention without departing from the spirit

of the same or the scope of the appended claims.

What is claimed and desired to be secured by Letters Patent is:

- 5 1. In a combined bench and folding cot, lazy tong side frames, a flexible top supported by the side frames, eye bolts pivotally joining the upper end of the articulated lazy tong bars, the eyes of said bolts of one of the side frames being disposed toward the eyes of the bolts of the other of said side frames, a continuous webbing strip threaded through said eye bolts to connect the side frames in cross-laced fashion and
- 10 15 a tension adjusting device joining the ends of said webbing strip, said flexible top passing down the sides of said lazy tong frames to engage said eye bolts at their ends opposite from the ends engaging said webbing strip.
- 20 2. In a combined bench and folding cot, lazy tong side frames, a flexible top, a plurality of spaced apart strips extending longitudinally of the top and reinforcing the same, said strips being secured at their ends to the end tie members of the lazy tong side frames, a reinforcing strip being stitched to said flexible top along each side respectively, said strips being stitched to the under side of the top with fullness allowed between the lines of stitch whereby when the strips lie along the upper ends of the side frames and extend down-wardly along the sides thereof the weight on the top 35 is transmitted to said stitched reinforcing strips through the inner lines of stitching.
- 25 3. In a combined bench and folding cot, lazy tong side frames, a flexible top, a plurality of spaced apart reinforcing strips extending longitudinally of the top and secured at their ends to the end tie members of the lazy tong side frames, a reinforcing strip being stitched to said flexible top along each side respectively, said strips being stitched to the lower side of the top with fullness allowed in the top between the lines of stitch, said top and stitched reinforcing strips extending over the tops of the lazy tong side frames to be attached 45 thereto at the sides thereof whereby weight on the top is transmitted to the ends of the lazy tong sides through the reinforcing strip and the inner line of stitches securing the same to the top.
- 40 45 50 55 5. In testimony whereof, we hereunto affix our signatures.

GEORGE A. LANSBERRY.
LOUIS A. HARTMAN.
VICTOR A. JASPERSON.
